CHOKE VALVE CONTROL

Handel Ashworth, Malverne, N. Y.

Application January 5, 1938, Serial No. 183,557

8 Claims. (Cl. 123—119)

This invention relates to choke valve controls. It is well recognized that internal combustion engines have difficulty in starting, and this is particularly true in cold weather. To overcome the difficulty, a charge abnormally rich in fuel is introduced into the cylinders during the initial revolutions of the engine. This is accomplished by closing the valve, known as the choke valve, which controls the supply of air, and drawing in substantially pure fuel when the engine is turned by the starting motor. It has been found that after the first few revolutions, and after the engine starts, that a continuation of the choke valve in the closed position floods the cylinder with fuel, and, not only stops it, but the flooding causes dilution of the lubrication in the crank case. If the choke valve is returned immediately to its full open position when the engine starts, the composition of the charge is so lean in fuel that the engine often stalls when it is placed under its normal load. Automotive engineers have long been seeking the ideal construction which automatically closes the choke valve until the engine starts and thereafter permits the choke valve to open progressively in accordance with the accepted requirements of efficient operation. Such requirements involve a quick return or cracking of the choke valve to the partly open position, where air may be instantaneously introduced into the substantially pure fuel charge; and from this partly open position, the choke valve should progress uniformly throughout the remainder of its path to the full open or normal running position.

I am aware of the fact that prior to my invention, others have constructed devices for controlling the same movements of the choke valve, but my invention is believed to embody several features which are a considerable improvement over these known devices. One advantage of my invention resides in a construction which makes it adaptable to customary internal combustion engines on the market, and particularly those engines used in standard automobiles, so that the said control may be incorporated when the automobile is built, or it may be sold as an accessory and installed with the minimum of expense in the limited space provided. My choke valve control is easily substituted as an accessory, although not limited to this use, for the customary manually operated rod control without expensive alteration; has fewer operating parts than other known choke controls performing the same operations; and promotes economy of manufacture owing to the simplified design and construction.

Among the advancements in the art flowing from my simplified construction are the features that enable the consolidation of the solenoid and dashpot structure in the same cylinder without modifying the cylinder walls to afford a by-pass for the fluid around the dashpot piston. Another advantage of my simplified structure allows the elimination of springs in the working parts because the present invention operates substantially by gravity. A further advantage in the present invention involves the use of an electromagnetic operating mechanism which obviates the use of caterulated rods and linkage of other known devices; and permits my invention to be used under conditions which require remote control of a positive nature where such rods and linkage would be cumbersome. For example, in automobile busses and trucks, or on motor boats, where the engine is situated at a great distance and in a tortuous direction from the customary position of the operator.

A still further advantage of my invention is that it promotes a quick cracking of the choke valve to the partly open position, and a slow uniform progress of the valve from the partly open position throughout the remainder of its return to the full open position. A further advantage of my invention resides in utilizing a metal of high thermal expansion properties, such as aluminum, or die casting metal, in making the housing cylinder so that the movements of the choke valve will be influenced by the heat of the cooling system of the engine. Were my device in direct contact with the heat of the engine, as by contact with the exhaust manifold, or the exhaust pipe, all the known liquids serviceable in dashpots would either evaporate or increase in viscosity through evaporation to an extent where a harmful effect in the operation would be produced. I place my housing cylinder for the dashpot in the area of the cooling system so that the heat exchange will be milder than the heat exchange in the area of the exhaust manifold and the exhaust pipe.

With the foregoing and other objects of the invention in view, my invention consists of a novel combination, arrangement and construction of parts as will be more particularly described and illustrated in the accompanying specification and drawing, but it will be understood that changes, variations, and modifications may be resorted to without departing from the spirit of the invention in the subjoined claims.

Referring to the drawing in detail wherein is

disclosed the preferred embodiment of my invention:

Figure 1 is a side elevation of a portion of an internal combustion engine, as mounted in an automobile, and showing an adaptation therewith of a choke valve control of the present invention.

Figure 2 is an enlarged detailed vertical section through the housing or cylinder with other parts of the engine in side elevation and partly broken away, and also showing the valved piston of the dash pot when the choke valve is open.

Figure 3 is a fragmentary sectional view through the cylinder of the choke control device showing the parts of the valved piston when the choke valve is being closed by the energized solenoid.

Figure 4 is a transverse section through the cylinder of the choke control showing the piston in plan.

Figure 5 is a sectional plan view taken on a plane directly above the cylinder of the choke control and looking downwardly.

Figure 6 is a wiring diagram of the electric circuit of the choke valve control of the present invention.

Referring to the drawing in detail, A indicates a remote control panel, such as an instrument board of an automobile, a control board of a motor boat, or any other remote position where a human operator may be located who wishes to control the conventional internal combustion engine B. Only those parts of the conventional internal combustion engine are shown, as is necessary to explain an application of the present invention. The internal combustion engine B has the customary circulating water cooling system and is equipped with a water cooled cylinder block 7, and bolted to the block is a water cooled cylinder head 8 provided with the customary channels 9 through which the cooling water circulates. A conventional down draft carburetor is indicated at 10, where the fuel is admitted for carbureting the air passing through the down draft pipe 11 from the air filter 12. The admission of the fuel mixture is controlled by the customary accelerator rod 13. The charge of air and fuel is delivered to the customary intake manifold 14 from where it is distributed to the cylinders and exploded, the resulting products of combustion passing out of the cylinders to the exhaust manifold 15 in the customary manner.

Above the carburetor 10, in the down draft pipe 11 there is rotatably mounted a choke valve shaft 16 to which is fixed in any suitable manner a round flat disk which forms the choke valve 17 of the butterfly type. This choke valve 17 is different and distinct from the throttle or accelerator valve which controls the admission of fuel. The choke valve 17 in the customary construction, and in my construction, is normally in the open position indicated in full lines in Figure 2 of the drawing, and remains in that position as long as the control of the present invention is inoperative. In my construction, the choke valve swings to open position by the weight of the actuating arm and connecting rod as will presently appear. In the closed position indicated by the dotted lines 18, in Figure 2, the choke valve substantially closes the passage in the down draft pipe 11 and substantially no air is admitted to the carburetor in which case a charge almost pure in fuel is drawn into the cylinders. The shaft 16 extends to the outside and beyond the pipe 11 and has a link 19 connected to it which turns the

shaft when the link is moved. The hollow dashpot cylinder C also forms a combination housing or casing for the cylindrical solenoid and other operating parts of the device. The cylinder is made of metal of a high coefficient of expansion 5 to heat. I prefer to make the cylinder in two parts, the numeral 20 indicating the upright cup-shaped bottom part and 21 designating the inverted cup-shaped top part. The open confronting ends of the top and bottom parts telescope 10 into each other and are secured together by the threaded joint 22. In an intermediate part of the cylinder properly insulated from the walls is a conventional solenoid 23. Adjacent the solenoid in the lower end of the cylinder is arranged the 15 dashpot member and in the top of the cylinder is a compartment 24 which accommodates the movement of the piston rod and actuating arm as will presently appear. A magnetically responsive piston rod made in two parts 25, 26 extends 20 through the bore 23a of solenoid 23 and has parts thereof projecting from each end of the solenoid. The upper part 25 of the piston rod is made of metal inactive to magnetism and the lower part 26 is metal responsive to magnetism such as iron 25 or steel. Part 25 is anchored fast in a socket in part 26 and the latter, in the lowermost position of the stroke of the piston rod shown in Figure 2, extends into the bore 23a a sufficient distance to lie in the field of magnetic force.

The dashpot member consists of the dashpot chamber 27 filled with liquid such as oil to the level indicated at 28. On the side of the bottom part 21 is an outset filling neck 29 to replenish the liquid and the passage of the neck is closed 35 by a screw plug 30. The lower part 26 of the piston rod extends into the oil in chamber 27 and has a reduced lower end 31 on the terminal of which is threaded a nut or collar 32. Fixed against the shoulder formed at the point where 40 the reduced part 31 joins with the part 26 of the piston rod is a round valve disk 33 and this valve has a peripheral depending lip 34. The dashpot piston 35 slides very freely on reduced part 31 of the piston rod within the limits of the valve 33 45 and the collar 32. The piston 35 has a normal clearance 60 between its periphery and the wall of the cylinder at room temperatures sufficient to permit the liquid to pass between during the reciprocation of the piston rod. However, the clearance increases when the walls of the cylinder expand under the temperature induced by locating the cylinder in the area of the cooling system. It will thus be seen that the entire range of movement of the piston is influenced by the thermal 55 expansion of the wall of the cylinder, which latter is in heat exchange relation with the cooling system of the engine, as will hereafter appear.

The upper face of the piston 35 is flat, and in an intermediate part of the piston are by-pass 60 openings 36 preferably four in number. The valve disk 33 is less in diameter than the piston to permit free passage of the liquid through the piston and around the valve on the up stroke of the piston rod when the solenoid is energized. When the piston abuts the valve, the by-pass openings are closed by the valve and the liquid can only pass between the periphery of the piston and the wall of the cylinder.

I prefer to mount the cylinder C on the head 8 of the cylinder block as close as possible to the channels 9 of the water circulating system that cools the engine. To mount the cylinder, there is a threaded socket 37 in the bottom wall 38 of the bottom part 21. The customary stud bolt 39 by 75

- which the head of the engine is bolted to the cylinder block is made a little longer than usual, and the free upper end seats in the socket 37 as shown in Figure 2. By this manner of mounting the axis of the cylinder extends perpendicular to the engine cylinder head, and the cylinder C is in heat exchange relation with the water cooling system, and remotely situated with respect to the exhaust manifold 15 and the exhaust pipe.
- 10 One projecting end, the upper end of the piston rod which projects free of the end of solenoid coil 23, bears against an intermediate part of an actuating arm 40. Arm 40 extends into a slot 41 in the side of top part 20 of cylinder C, and has the inner end pivoted at 42 to the cylinder C. The intermediate portion of arm 40 extends diametrically across the cylinder and swings in the upper chamber 24. The slot 41 limits the swinging movement of arm 40, the dotted line position in Figure 2 indicating its uppermost position when the choke valve 17 is closed and the full line position shown in Figure 2 showing the normal position when the choke valve 17 is in full open position and the solenoid 23 deenergized. A portion of actuating arm 40 protrudes outside the cylinder C and this portion is provided with a longitudinal slot 43 which co-operates to furnish adjustment of the choke valve 17.
- 30 A connecting rod 44 is provided near the lower end with a ball and socket joint 45 to accommodate swinging movement of the rod. The lower terminal of the connecting rod 44 has an offset threaded stem 46 which extends through the slot 43 in arm 40 and this stem receives the nut 47 which secures the connecting rod and arm together. The upper end of connecting rod 44 is connected to the outer end of link 19 which turns the choke valve shaft 16. This connection 40 is shown at 48 and consists of forming an offset teat on the end of the connecting rod which passes through an opening in the end of link 19 and the inner end of the teat is prevented from detachment by the cotter pin extending through an opening in the teat all of which is shown in Figure 1. Since the nut 47 makes a fixed connection between the connecting rod 44 and the arm 40, the ball and socket joint 45 permits the connecting rod to have a swivel joint in its length which is necessary in translating movement from the actuating arm to the link 19. To permit circulation of air in the cylinder C, I make openings 49 in the sides of the upper part 20. I also prevent liquid in the dashpot chamber 27 from getting into the solenoid coil 23, by securing a rubber or fiber washer 51 in the lower end of the upper part 20 of cylinder C. Electricity to operate the solenoid 23 is supplied from a battery 52, which is grounded at 53, by an electrical conductor wire 54 which conductor wire connects with the switch 55 on the panel A. Leading from the switch and connected to the solenoid coil 23 is an electrical conductor wire 56. The solenoid is grounded at 57.
- 65 The parts of my choke valve control are substantially in the position shown in Figure 2, when the engine B is at rest. In starting the engine B, switch 55 is closed at the same time the starting motor for the engine is brought into operation. By closing switch 55, solenoid 23 is energized and piston rod moves upwardly with the valved piston parts in the position shown in Figure 3, which action closes choke valve 17 to the dotted line position 18 shown in Figure 2.
- 70 When the cylinders of the engine have been primed with a charge rich in fuel, the switch 55 is opened whereupon the solenoid is deenergized. The weight of the piston rod, which obviously forms the core of the solenoid coil, permits it to sink in the liquid of the dashpot chamber 27 until the piston valve 33 encounters the materially slower sinking piston 35, from which point of encounter the piston rod is retarded by the dashpot action throughout the remaining distance of its stroke, because the sole path for displacing the liquid is the clearance space 60 between the periphery of the piston and the wall of the cylinder.
- 75 The distance the piston rod freely drops when the solenoid 23 is deenergized, permits the weight 15 of the connecting rod 44 and the actuating arm 40 to partially open or crack the choke valve 17 to the dotted line position 58 shown in Figure 2. The quick cracking or partial opening of the choke valve 17 simultaneously admits sufficient 20 air to thin the rich fuel and allows the engine to be accelerated when placed under its load. As the piston and weight of the piston rod now bearing on the piston slowly sinks in the liquid under dashpot action, the choke valve 17 uniformly and progressively opens to the full line 25 position shown in Figure 2, allowing a greater amount of air to enter the carburetor as the valve opens.
- If the engine is warm when it is started, and 30 it is necessary to choke the engine by closing the choke valve 17, the cylinder C having a high coefficient of thermal expansion, will have expanded by the heat radiated from the cooling system of the engine on which the cylinder is 35 mounted. In this case, there will be greater clearance between the wall of the cylinder C and the periphery of the piston 35 thereby allowing quicker movement of the choke valve because the liquid of the dashpot will be displaced in accordance with the proportional increase in the clearance space, and this quickened movement prevails throughout the entire range of movement of the piston rod. Since there is a normal clearance 60 between the peripheral edge of the 40 piston and the wall of cylinder C, the oil or other liquid in the clearance space will act as an insulator and prevent a substantial amount of heat from expanding the piston to correspond with the expansion of the cylinder C. An 45 appreciable quickening effect is noticeable from the thermal expansion of the cylinder C on the return stroke of the piston rod when initially starting a cold motor because some heat is imparted to the cooling water and transferred to 50 the cylinder C during the interval of time the device is in operation.
- In Figure 2 of the drawing I have shown one way of fastening the solenoid 23 in the upper part 20 of cylinder C, although other ways of 55 fastening may be devised. In assembling the solenoid 23 in the upper part 20, the said solenoid is slid into the upper part of the cylinder until the customary fiber or rubber washer 63 that is found at the top of the conventional solenoid abuts against small outstanding teats 62 near the top of part 20. These teats may be made by making indentations in the walls of the upper part 20 of the cylinder as shown, or they may be made in other ways. After the solenoid 65 is inserted in the upper part 20, then the upper part is screwed into the lower part 21 until the free edge of the lower part bears against the shoulder 64 on the upper part 20. In the screw joint 22, a hole is then drilled and tapped with 70 75

5 threads to receive the screw 61. This screw 61 is screwed into the hole until the inner end extends into the cylinder under the fiber or rubber washer 51 on the bottom of the solenoid 23, and the inner end of the screw prevents the solenoid 5 from becoming dislocated in the cylinder during the contraction and expansion of the cylinder under the influence of the heat of the cooling system.

10 Having described my invention, what I claim is:

1. In an internal combustion engine equipped with a cooling system, the combination with a normally open retractile choke valve of the carburetor thereof, of manually controlled electro-magnetic means for moving the choke valve in one direction opposed to the direction of the retractile force, and a dashpot provided with a variable rate of movement within the limits of 15 its stroke to retard the retraction of the choke valve upon the release of the electro-magnetic means, and the entire range of the movement of the dashpot further controlled by the temperature of the cooling system.

25 2. In an internal combustion engine, the combination with a normally open choke valve thereof, of a cylinder, a solenoid mounted in a part of the cylinder, a dashpot chamber in another part of the cylinder, a magnetically responsive 30 piston rod extending through and projecting from each end of the solenoid, a portion of the piston rod extending into the dashpot chamber and another portion forming the core of the solenoid, a valved piston on the portion of the 35 piston rod in the dashpot chamber resisting counter movement of the piston rod relative to the magnetic force, connecting means between the free end of the piston rod and the choke valve, and means for supplying electricity to 40 energize the solenoid.

3. In an internal combustion engine, the combination with a normally open choke valve thereof, of a cylinder, a solenoid mounted in a part of the cylinder, a dashpot chamber in another 45 part of the cylinder, a magnetically responsive piston rod extending through and projecting from each end of the solenoid, a portion of the piston rod extending into the dashpot chamber and another portion forming the core of the 50 solenoid, a piston on the portion of the piston rod in the dashpot chamber resisting counter movement of the piston relative to the magnetic force, connecting means between the free end of the piston rod and the choke valve, means for 55 supplying electricity to energize the solenoid, and the cylinder formed of metal of a high coefficient of thermal expansion so as to control the movement of the piston in accordance with the temperature of the engine.

60 4. In an internal combustion engine, the combination with a normally open choke valve thereof, of a cylinder, a solenoid mounted in a part of the cylinder, a magnetically responsive piston rod extending through and projecting from each 65 end of the solenoid, a portion of the piston rod extending into the dashpot chamber and another portion forming the core of the solenoid, a piston on the portion of the piston rod in the dashpot 70 chamber resisting counter movement relative to the magnetic force, connecting means between the free end of the piston rod and the choke valve, means for supplying electricity to energize

the solenoid, said connecting means including an actuating arm pivotally connected with the cylinder and engageable with the free end of the piston, and a connecting rod adjustably connected to the actuating arm and connected with 5 the choke valve.

5. In an internal combustion engine equipped with a water cooling system, the combination with a normally open choke valve of the carburetor thereof, of a cylinder formed of a metal having a relatively high coefficient of thermal expansion, an electro-magnetic means mounted in a part of the cylinder for urging the choke valve to closed position upon the energization thereof, means for connecting the electro-magnetic means with the choke valve, a dashpot chamber containing liquid in another part of the cylinder, a piston in the liquid in the dashpot chamber and connected with the electro-magnetic means to resist movement thereof, said cylinder positioned in the area of the cooling system of the engine in heat exchange relation therewith to vary the resistance to the movement of the piston in accordance with the thermal expansion of the said cylinder as influenced by the 20 temperature of the cooling system of the engine.

6. In an internal combustion engine, the combination with a normally open choke valve of the carburetor thereof, of a cylinder, a solenoid mounted in an intermediate portion thereof, a 30 dashpot chamber containing liquid in another portion thereof adjacent the solenoid, a magnetically responsive piston rod forming a core in the solenoid and projecting from each end thereof, one projecting end of the piston rod disposed in the liquid of the dashpot chamber, a valved piston on the piston rod in the liquid of the dashpot chamber resistant to the passage of the piston through the liquid in a direction counter to the magnetic force on the piston rod induced by the energized solenoid, connecting means engaging the free end of the piston rod and choke valve for operating the choke valve in response to the movement of the piston rod, manually controlled means for supplying electricity to energize 45 the solenoid, said valved piston being movably mounted on the piston rod for limited movement to reduce resistance to the movement of the piston rod in the direction of the magnetic force exerted by the solenoid and permit a reduction 50 in resistance to the movement of the piston rod within the limited movement when the piston rod moves in the opposite direction.

7. In an internal combustion engine, the combination with a normally open choke valve of the carburetor thereof, of electro-magnetic means for closing said choke valve, a dashpot coating with the electro-magnetic means to retard the return of the choke valve to open position, and automatic means to vary the effectiveness of 60 the dashpot during its stroke.

8. In an internal combustion engine, the combination with a normally open retractile choke valve of the carburetor thereof, of well controlled electro-magnetic means for moving the choke 65 valve in one direction opposed to the direction of retraction, and a dashpot having a varied rate of movement within the limits of its stroke to retard the retraction of the choke valve upon the release of the electro-magnetic means.

HANDEL ASHWORTH.

CERTIFICATE OF CORRECTION.

Patent No. 2,121,392.

June 21, 1938.

HANDEL ASHWORTH.

It is hereby certified that error appears in the printed specification of the above numbered patent requiring correction as follows: Page 4, second column, line 64, claim 8, for the word "well" read will; and that the said Letters Patent should be read with this correction therein that the same may conform to the record of the case in the Patent Office.

Signed and sealed this 5th day of July, A. D. 1938.
